J. G. Jones.

UNITED STATES PATENT OFFICE.

DANIEL E. POWERS, OF NEW YORK, N. Y., ASSIGNOR, BY DIRECT AND MESNE ASSIGNMENTS, TO THE PATENT PAPER CIGAR BOX COMPANY, OF SAME PLACE.

CIGAR-BOX.

SPECIFICATION forming part of Letters Patent No. 325,627, dated September 1, 1885.

Application filed September 2, 1884. Renewed April 22, 1885. (No model.)

To all whom it may concern:

Be it known that I, DANIEL E. POWERS, a citizen of the United States, residing at New York, in the county of New York and State of New York, have invented certain new and useful Improvements in Cigar-Boxes, of which the following is a specification, reference being had therein to the accompanying drawings.

The object of this invention is to provide a cheap cigar-box of paper or straw board of sufficient strength to withstand the usual pressure incident to the packing of the cigars.

In the accompanying drawings, Figure 1 is a plan of the under side of a blank for the body of a box made in accordance with this invention. Fig. 2 is a perspective view of said blank when folded into proper position to form the body of the box, shown as provided with a lid and with one corner broken away. Fig. 3 is a plan of the under side of the folded blank shown in Fig. 2. Fig. 4 is a perspective view of the completed box.

Similar letters of reference indicate corresponding parts in the different figures.

In the drawings, A represents the blank for the body of the box, and B the lid therefor. The blank A, composed of thick straw-board or board composed of other suitable paper-stock, is rectangular in shape, recessed at its sides, and comprises a rectangular bottom, *a*, rectangular side flaps, *b b*, rectangular end flaps, *c c*, and re-enforcing square or rectangular semi-end flaps *d d d d*, attached to the ends of the rectangular side flaps.

The side flaps, *b b*, extend throughout the recessed portion of the blank, and are partially severed from the bottom *a*, to which they remain attached by means of parallel longitudinal scores *z z*, which are cut or impressed in the blank at distances from the recessed edges equal to the interior depth of the box to be formed. The rectangular end flaps, *c c*, are partially severed from said body *a*, to which they remain attached by parallel transverse scores *y y*, extending between the longitudinal scores *z z*, and impressed or cut in the blank at distances from the end edges thereof equal to the depth of the box to be formed plus the thickness of the blank.

The re-enforcing semi-end flaps, *d d d d*, are completely severed from the end flaps, *c c*, by short longitudinal cuts *x x x x*, which are continuous with the longitudinal scores *z z*, and extend from the ends thereof and in line therewith to the end edges of the blank, and said semi-end flaps are partially severed from the side flaps, *b b*, to which they remain attached by short transverse scores *w w w w*, which extend inward from the side edges of the blank to the cuts *x x x x* at right angles to said cuts, being the thickness of the blank nearer to the end edges thereof than the transverse scores *y y*.

In forming the box from the blank thus described the end flaps, *c c*, are first folded at right angles to the bottom *a* on the lines of the transverse scores *y y*. The side flaps, *b b*, are then folded up against the end flaps on the lines of the longitudinal scores *z z*. The semi-end flaps attached to the side flaps are then folded laterally on the short transverse scores *x x x x* over against the end flaps. These semi-end flaps meet at the center of the end flaps, and, together with said end flaps, constitute the ends of the box, which are of double and uniform thickness throughout.

The blank thus folded is properly cemented or pasted, and covered with a layer of paper, which hides the joints and assists in strengthening the box. Owing to the recesses in the sides of the blank along the side flaps said side flaps, when folded, are of less height than the ends of the box, which latter project above the sides a distance equal to the thickness of the cover B. The cover is attached at its rear edge by means of a flexible cloth or other suitable hinge to the rear side of the box, and suitable catches or fastening devices, C, are attached to the front edge of the lid and front side of the box.

When the lid is closed, it shuts between the end flaps, and its top surface is flush with the upper edges thereof. As thus constructed the box is strong, cheap, and durable.

I claim as my invention—

1. A rectangular blank for cigar-boxes recessed at its sides, and provided with parallel longitudinal scores along the bottom section,

with longitudinal cuts which are continuous with said longitudinal scores and extend from the ends of said scores to the end edges of the blank, with transverse scores which connect the meeting-points of said longitudinal cuts and longitudinal scores, and with short transverse scores which extend from said longitudinal cuts to the side edges of the blank, being located endward from said transverse scores a distance equal to the thickness of the blank, substantially as described.

2. A blank for cigar-boxes consisting of the bottom section, *a*, end flaps, *c c*, side flaps, *b b*, and semi-end flaps, *d d d*, attached to the side flaps and adapted to meet flush against

said end flaps, said end and semi-end flaps being deeper than the side flaps, substantially as described.

3. A cigar-box composed of paper-board, and provided with double ends extending above the sides, and with a cover which shuts between said ends flush with the upper edges thereof, the inner layers of the ends being integral with the bottom of the box, and the outer layers thereof being in sections integral with the sides of the box, substantially as described.

DANIEL E. POWERS.
